DESIGN FOR A MASSAGER

Fred F. Latshaw, Altadena, Calif.

Application November 6, 1944, Serial No. 116,166

Term of patent 3½ years

(Cl. D83—1)

To all whom it may concern:

Be it known that I, Fred F. Latshaw, a citizen of the United States, residing at Altadena, in the county of Los Angeles and State of California, have invented a new, original, and ornamental Design for a Massager, of which the following is a specification, reference being had to the accompanying drawing, forming part thereof.

Fig. 1 is a top plan view of a massager, showing my new design.

Fig. 2 is a side elevation of the same.

Fig. 3 is an elevation of the same in a plane at right angles with Fig. 2.

Fig. 4 is a bottom plan view thereof.

I claim:

The ornamental design for a massager, as shown.

FRED F. LATSHAW.
